Primary Examiner — Keith J Wilson(57) **CLAIM**

The ornamental design for a locking part for paint spray gun as shown and described.

DESCRIPTION

1. Locking part for paint spray gun

1.1 : Perspective

1.2 : Front

1.3 : Back

1.4 : Left

1.5 : Right

1.6 : Top

1.7 : Bottom

1. The application of the present appearance design: used as a locking part of spray paint cup or gravity cup for spray gun, used for locking the inner cup and outer cup of paint spray gun; 2. The key point of the present appearance design: the shape; 3. The figure or picture which fully shows the key point of the present appearance design: perspective view.
